Fig. 14.

Fig. 15.

FIG. 1 is a perspective view of a line tap valve showing my new design;

FIG. 2 is a front view thereof;

FIG. 3 is a right side view thereof;

FIG. 4 is a rear view thereof;

FIG. 5 is a left side view thereof;

FIG. 6 is a top plan view thereof;

FIG. 7 is a bottom plan view thereof;

FIG. 8 is a perspective view of a modified form of the line tap valve shown in FIG. 1;

FIG. 9 is a perspective view of a second modified form of the line tap valve shown in FIG. 1;

FIG. 10 is a front view of FIG. 9;

FIG. 11 is a right side view of FIG. 9;

FIG. 12 is a rear view of FIG. 9;

FIG. 13 is a left side view of FIG. 9;

FIG. 14 is a top plan view of FIG. 9;

FIG. 15 is a bottom plan view of FIG. 9; and

FIG. 16 is a perspective view of a third modified form of the line tap valve shown in FIG. 1.

I claim:

The ornamental design for a line tap valve, as shown and described.
